J. W. BODKER

GARMENT HANGER

Filed June 24, 1925

Inventor

J. W. Bookier

Rooney, Rooney. Attorneys

UNITED STATES PATENT OFFICE.

JOHN W. BODKER, OF PONCHATOULA, LOUISIANA.

GARMENT HANGER.

Application filed June 24, 1925. Serial No. 39,334.

To all whom it may concern:

Be it known that I, JOHN W. BODKER, a citizen of the United States, residing at Ponchatoula, in the parish of Tangipahoa and State of Louisiana, have invented certain new and useful Improvements in Garment Hangers, of which the following is a specification.

This invention relates to garment hangers and one object of the invention is to provide a garment hanger formed of adjustable sections capable of being extended to fit the garment to be suspended and which may be retracted into a compact mass and conveniently placed in a suit case or drawer when not in use.

Another object of the invention is to provide a garment hanger formed from strands of wire so connected that the sections will be well braced and prevented from having transverse movement when extended or retracted.

This invention is illustrated in the accompanying drawing, wherein—

Figure 1 is a perspective view showing the hanger in the extended position for use;

Fig. 2 is a side elevation showing the hanger in the folded or retracted position;

Fig. 3 is a sectional view taken on the line 3—3 of Fig. 1, and

Fig. 4 is a transverse sectional view taken on the line 4—4 of Fig. 1.

The garment hanger includes a body portion formed of sections which are indicated in general by the numerals 1 and 2 and suspending means which is indicated in general by the numeral 3. The sections 1 and 2 which form the body portion of the garment hanger are of duplicate construction and each is formed from a strand of resilient wire which is bent intermediate its length to provide a bridge portion 4 from which extends a hook 5 formed by doubling the portion of the wire from which the bridge is formed and then bending this doubled portion of the wire into a hook. These hooks can be conveniently used for suspending a skirt or other garment. Arms 6 and 7 extend from the bridge portion 4 of each section, and these arms 6 and 7 have

their inner free end portions crossed, as shown at 8 in Fig. 3, and terminate in outwardly bent end portions 9 which are bent back upon themselves to provide elongated eyes 10. The arms of the sections 1 and 2 extend in longitudinal overlapping relation to each other with the arms of the section 2 disposed over the arms of the section 1 and the eyes 10 slidably receive the arms so that the arms will be permitted to readily slide longitudinally of each other but will be prevented from having movement transversely of each other. It will be noted from an inspection of Fig. 3 that the arm 6 of the section 1 and the arm 7 of the section 2 extend between the arm 6 of the section 2 and the arm 7 of the section 1 and across the same in diagonal relation thereto between the eyes 10 of the two sections. Therefore, the intermediate portion of the garment hanger will be very firmly braced. This construction also serves to cause the extended sections to be braced against downward movement so that the hanger will support a heavy garment, such as an overcoat or the like, without being readily bent out of shape.

The suspending means 3 includes a hook 11 which is formed from a strand of wire which has one end portion bent to provide a support-engaging bill 12 and its other end portion bent to provide an eye or loop 13. Links 14 are carried by the hook and extend in depending relation thereto. Each link 14 is also formed of a strand of wire, the said strand being bent intermediate its length to provide an eye 15 and depending arms 16. The arms 16 extend downwardly in diverging relation to each other transversely of the body portion and have their end portions formed into eyes 17 which fit loosely into the eyes 10. Since the eyes 15 have loose engagement with the eye or loop 13 of the hook 11 and the eyes 17 have loose fitting engagement with the eyes 10, the links 14 will be free to move towards and away from each other longitudinally of the body and, therefore, the sections of the body may be readily moved longitudinally of each other into

and out of a retracted position. When the sections of the body are in the retracted position shown in Fig. 3, the hook may be swung downwardly so that its bill 12 extends between the arms 16 of one of the links 14. When in this position, the hook will be so disposed that it will be out of the way and not liable to catch in clothing or other articles packed in a suit case. When it is desired to make use of the garment hanger, it is merely necessary to swing the hook upwardly and hold it by the bill with one hand and then loosely grasp the body portion between the links 14 with the other hand. The hook can then be drawn upwardly and as it is moved away from the body portion the links will be swung toward each other longitudinally of the body and the two sections of the body will be caused to move towards an extended position. If it is found that the sections of the body are not extended a sufficient distance, it is merely necessary to grasp the links adjacent their lower ends and press them towards each other and this will cause the sections of the body to be extended their full extent. When the hanger is to be folded, the links are grasped near their lower ends and moved away from each other. This will cause the sections of the body to be moved to the retracted position and the bill of the hook can be easily swung downwardly to the position shown in Fig. 2. There has, therefore, been provided a garment hanger which can be entirely formed from strands of wire and will be strong and durable and very easy to move into and out of a position for use.

Having thus described the invention, I claim:

1. A garment hanger comprising a body portion formed of separate sections each having longitudinally extending arms crossed adjacent their inner ends and terminating in eyes slidably securing the arms of the other section to movably connect the sections in overlapping relation and permit longitudinal adjustment thereof, and suspending means disposed between and connected with the inner ends of said sections.

2. A garment hanger comprising a body portion formed of separate sections each having longitudinally extending arms crossed adjacent their inner ends and terminating in eyes slidably securing the arms of the other section to movably connect the sections in overlapping relation and permit longitudinal adjustment thereof, a support-engaging member, and links loosely connected with said support-engaging member and having depending arms loosely engaged in the eyes at the inner ends of said sections.

3. A garment hanger comprising a body portion formed of separate sections each having longitudinally extending arms

crossed adjacent their inner ends and terminating in eyes slidably securing the arms of the other section to movably connect the sections in overlapping relation and permit longitudinal adjustment thereof, a support-engaging member formed as a hook provided with an eye at its lower end, and links loosely mounted in the eye of said hook and extending downwardly therefrom in diverging relation to each other longitudinally of the body portion, each link having depending arms extending downwardly in diverging relation to each other transversely of the body portion, and the arms of said links terminating at their lower ends in eyes loosely engaged with the eyes at the inner ends of said sections.

4. A garment hanger comprising a body portion formed of separate sections and each of said sections being formed of a strand of resilient wire bent to provide a bridge at the outer end of the section and arms extending from said bridge, the arms of one section extending in overlapping relation to the arms of the other section and each section having its arms crossed and at their free ends terminating in eyes slidably engaged with the arms of the other section between their point of crossing and the bridge connecting their outer ends, and suspending means disposed above the overlapped portions of said sections and engaged with eyes at the inner ends of said arms.

5. A garment hanger comprising a body portion formed of separate sections and each of said sections being formed of a strand of resilient wire bent to provide a bridge at the outer end of the section and arms extending from said bridge, the arms of one section extending in overlapping relation to the arms of the other section and each section having its arms crossed and at their free ends terminating in eyes slidably engaged with the arms of the other section between their point of crossing and the bridge connecting their outer ends, suspending means disposed above the overlapped portions of said sections and including a support-engaging element provided with an eye at its lower end, and links loosely mounted in the eye of said support-engaging element and extending downwardly therefrom in diverging relation longitudinally of the sections and loosely engaged in the eyes at the inner ends of the arms of said sections.

6. A garment hanger comprising a body portion formed of separate sections and each of said sections being formed of a strand of resilient wire bent to provide a bridge at the outer end of the section and arms extending from said bridge, the arms of one section extending in overlapping relation to the arms of the other section and each section having its arms crossed and at their free ends terminating in eyes slidably engaged

with the arms of the other section between their point of crossing and the bridge connecting their outer ends, suspending means disposed above the overlapped portions of said sections and including a support-engaging element provided with an eye at its lower end, and links loosely mounted in the eye of said support-engaging element and extending downwardly therefrom in diverg-

ing relation longitudinally of the sections 10 and each including arms diverging transversely of the sections and terminating in eyes at their lower ends loosely engaged in the eyes at the inner ends of the arms of said sections.

15

In testimony whereof I affix my signature

JOHN W. BODKER. [L.S.]
